UNITED STATES PATENT OFFICE.

HARTLEY O. BAKER AND WILLIAM P. COOK, OF PUEBLO, COLORADO, ASSIGNEES TO
THE BAKER STEAM MOTOR CAR AND MANUFACTURING CO., INC., OF PUEBLO,
COLORADO.

STEAM-CONDENSER.

1,384,737.

Specification of Letters Patent. Patented July 19, 1921.

Application filed May 13, 1918. Serial No. 234,167.

To all whom it may concern:

Be it known that we, HARTLEY O. BAKER and WILLIAM P. COOK, citizens of the United States, residing at Pueblo, in the county of 5 Pueblo and State of Colorado, have invented certain new and useful Improvements in Steam-Condensers; and we do hereby declare the following to be a full, clear, and exact description of the invention, such as 10 will enable others skilled in the art to which it appertains to make and use the same.

This invention relates to steam condensers and the object of the invention is to provide an improved condenser especially adapted 15 for steam automobiles and motor boats but which may also be applied to steam trucks and even to stationary engine condensers.

The object of the invention is the provision of a condenser unit composed of a series 20 of parallel plates so arranged and formed as to provide alternate steam and air passages of novel form, to efficiently condense the steam and provide for large capacity.

With these objects in view the invention 25 consists in the improved construction, arrangement and combination of the parts of a device of the character specified, which will be hereinafter fully described and afterward specifically claimed.

30 In order that the construction and operation thereof may be readily comprehended, we have illustrated an approved embodiment of our invention in the accompanying drawings, and will now proceed to fully describe the same in connection with said drawings, in which—

Figure 1 represents a diagrammatic plan view of our improved system.

Fig. 2, a view, in plan, of a primary condenser, part of one side being broken away 40 showing part of the interior construction in section,

Fig. 3, a vertical, longitudinal, sectional view on the plane indicated by the broken away section line 3—3 of Fig. 2,

Fig. 4, a transverse, vertical sectional view on the plane indicated by the broken line 4—4 of Fig. 2.

Fig. 5, a transverse section on the line 50 5—5 of Fig. 1, and

Fig. 6, a rear view of the condenser proper or main condenser, on the line 6—6 of Fig. 1.

Like reference characters mark the same

parts wherever they appear in a plurality of 55 the figures of the drawings.

Referring specifically to the drawings, and particularly to Fig. 1, 15 indicates the engine, which in this system is mounted on the rear axle 16 of the car, and 17 is the exhaust pipe from the engine which leads to the rear end of the primary condenser 18, which is open at front and rear to permit the air to pass through, especially when the 60 car is in motion, to more quickly cool the 65 steam passing through as hereinafter described.

To increase and facilitate the speed of 65 passage of the air through the primary condenser, we may employ a power fan, as at 19, in Figs. 2 and 3, which fan may be driven from any suitable power, such as an electric motor, or a steam exhaust fan, by suitable belting and pulley, said fan 19 being located in the open forward end of 70 the primary condenser, which is flared or 75 funnel shaped, to gather in the air, as shown at 20.

From the primary condenser 18 the 80 exhaust steam, partly cooled, passes through a pipe 21 to the condenser proper 22 said pipe being finned, as at 23, to increase its cooling capacity to still further cool the steam on its way to the condenser proper.

The steam condenser 22, as shown, is in 85 the form of an ordinary automobile radiator, of honeycomb type.

The steam from the finned pipe 21 passes through a steam hose, as at 24, into and through a series of pipes 25, 26, 27 and 28, 90 into the shell of the condenser proper, the pipes 25 and 26 discharging at one side of a partition 29, and the pipes 27 and 28 at the other side of said partition, which divides the shell of the condenser into two 95 chambers through which the steam passes.

There may be more or less than four of 100 these pipes and there may be a number of partitions to suit the number of pipes, the object being to divide the steam entering the condenser into a number of streams to prevent the discharge of the whole volume of steam on one point thereof, which has heretofore been found very objectionable in that it overheated that part receiving the 105 great volume of steam and often melted fusible parts.

The steam, after being cooled in the con-

denser proper and reduced to liquid form, passes through a pipe 30 at the bottom and is carried back to the water tank of the engine.

- 5 Referring particularly to Figs. 2, 3 and 4, our primary condenser 18 comprises a rectangular hollow body in which are formed passageways for the steam between vertical, longitudinal sheets 31 and 32, in 10 pairs at a short distance apart joined, at their rear ends to close that end of the passageways, by the rear end 33 of the body and closed at their front terminals at 34, the exhaust pipe 17 communicating with the 15 upper edges of the passageways, as at 35 (Fig. 3) at the rear ends thereof, and the pipe 21 leading from the primary condenser communicating with the lower portions of the passageways in a like manner as at 36. 20 The upper and lower edges of the sheets 31 and 32 are secured to the top and bottom of the condenser 18, which has an elongated open ended casing, and said sheets divide the air passage.
- 25 The sheets are sinuous and parallel as shown in Fig. 2, to make the steam passageways tortuous and insure greater contact with the inner surface of the sheets by the steam, and the pairs forming the several 30 passageways are corrugated transversely throughout the sinuous portions to insure further contact of the steam with the walls, as best shown in dotted lines in Fig. 2. The sinuous portions or waves are of relatively 35 large curvature and size to give the air and steam a gentle sinuous motion while the corrugations are small to give the fluid a rapid transverse deflection from side to side as same pass through the sinuous portions.
- 40 Besides facilitating the contact of the

passing steam with the interior surfaces of the walls thereof, this construction further facilitates the cooling of the walls of the passageways by causing greater contact therewith of the air passing through the 45 primary condenser.

The passage of the exhaust steam through the primary condenser, the finned pipe, and the condenser proper, constructed as described, thoroughly cools and condenses it, 50 as we have proved by long experiment, the effect being more complete and sure than with any form of condenser heretofore available.

The utility and simplicity of our invention will be evident from the foregoing and we desire to be understood that changes and variations may be made from the specific construction described, without departing from the spirit and scope of the invention. 55

Having thus fully described our invention, what we claim as new and desire to secure by Letters Patent of the United States is:

A steam condenser comprising a shell having parallel sheets therein extending longitudinally and arranged in pairs to provide alternate air and steam passages, said sheets having relatively long sinuous portions throughout their lengths, and the sinuous portions having smaller transverse corrugations throughout the length thereof. 65

In testimony whereof we have signed our names to this specification in the presence of two subscribing witnesses.

HARTLEY O. BAKER.
WILLIAM P. COOK.
